UNITED STATES PATENT OFFICE.

MACK M. SCHWER, OF HACKENSACK, NEW JERSEY.

MANUFACTURE OF PAPER CONTAINERS.

Application filed November 25, 1922. Serial No. 283,161.

To all whom it may concern:

Be it known that I, MACK M. SCHWER, a citizen of the United States, residing at Hackensack, in the county of Bergen and State of New Jersey, have invented certain new and useful Improvements in the Manufacture of Paper Containers, of which the following is a specification.

This invention relates to the art of forming tubular bodies composed of yielding sheet material with tapered portions, for example, bodies composed of paper and adapted to have, or to have attached thereto, bottom-forming walls and to then serve as containers for milk and other substances. The invention contemplates placing the body to be formed on a tapered mandrel and then applying constricting pressure to the body in a zone cutting the tapered portion of the mandrel and simultaneously causing relative rotation around the axis of the body as between the said body and the pressure-applying medium and also effecting movement of one of the latter relatively to the other lengthwise of said axis and so that said pressure will progress in the direction of convergence of the taper. The result of this procedure will be to produce folds or creases which all lap in the same direction around the axis of the body but which are generated indiscriminately as to position lengthwise of the body and as to spacing from each other and whose extent or length varies, but which in most cases, though not invariably, extend to the transverse plane where the treatment is terminated, wherever they may start, and usually, though not invariably, increase in width from the point of generation clear to said plane. The advantages, among others, are that the product can be formed quickly and with the use of very simple means and that different degrees or kinds of taper may be produced without change of any kind except of one mandrel for another. Usually for milk bottles and the like the sheet material may be paper that is impregnated or otherwise charged with paraffin wax or any equivalent tacky substance that will impart to the paper the quality of retaining folds or creases formed therein in a way now well known in the art of manufacturing paper liquid containers.

The constricting pressure is not necessarily pressure acting at every or even substantially every point in a circumferential line around the body being treated, although in

the best form of the invention and in the example herein illustrated and described that is the case, the pressure exerting medium being an attenuated flexible device, such as a cord or wire. When the pressure-applying medium is adapted to apply the pressure so that it acts at substantially every point in a circumferential line around the body being treated, rather than at intervals in such line, the creases or folds will be generated at frequent intervals, which will improve the appearance of the article and also insure its greater stability and desirably reduce the width of the creases or folds where, at the smaller part of the taper, they develop into their greatest width.

Having thus outlined my invention I will now describe one way in which it may be performed and an apparatus which may be used for the purpose.

In the drawings,

Fig. 1 is a front elevation, partly in section, of an apparatus for forming tubular bodies composed of yielding sheet material with tapering portions in accordance with this invention;

Figs. 2 and 3 are fragmentary elevations, partly in section, of the mandrel and the tubular body showing the latter after the tapering has been effected and in two different stages of further shaping a portion which adjoins the thus-tapered portion;

Fig. 4 is a fragmentary side elevation of the article produced by said apparatus; and

Fig. 5 is a similar view but showing a part of the article in section and after it has undergone a shaping operation performed thereon independently of this invention.

The tubular body A of yielding sheet material, as paper charged with paraffin wax, is placed on a mandrel comprising a cylindrical portion a', which snugly fits the body A, and a tapered portion a"; one end of the body A is flush with that of the mandrel, both being at right angles to their axis, but the other end of the body A projects beyond the tapered end of the mandrel.

The mandrel with the body A thereon is placed between two face plates b and c, the former having a square plug b' to fit a corresponding recess in the end of the mandrel and the latter having a projecting cylindrical boss d of slightly greater diameter than the smaller end of the portion a" and adapted to have dowel-connection with the

mandrel as indicated at *c'* (Fig. 1); as will appear the boss *d* is an enlarged extension, in effect, of the mandrel, although it is separable therefrom.

5 The face plate *b* is part of a rotary driving member which includes the shaft *e* on which the face plate is arranged and a pulley *f*, also on the shaft, said shaft being journaled in a stand *g*; *h* is a belt for driving the pulley.

10 The face plate *c* has a cone bearing at *i* on the end of a spindle *j* on which it is suitably swiveled. This spindle is splined in a stand *k* and may be advanced toward or 15 retracted from face plate *b*, so that the two face plates may be made to clamp or release the mandrel and body *A*, by the threaded stem or screw *l* engaged with the spindle and swiveled at *m* in a part of the stand and 20 having a hand-wheel *n* for rotating it.

25 The device for applying constricting pressure in the present case is a cord or wire *o*. One end is attached to an eye *p* on a carriage *q* which may travel parallel with the axis of the mandrel on a bed or frame *r* supporting the stands *g* and *k*. A bight may be taken in the other end of the device *o* around a hook *s* on the carriage. The carriage has a nut *t* in engagement with the 30 rotary screw *u* journaled in frame *r* parallel with the axis of the mandrel and connected with shaft *e* by gearing *v* in such manner that when the shaft as viewed from the left in Fig. 1 is rotated clockwise the direction 35 of rotation of the screw will be such as to cause the carriage to travel to the right in Fig. 1, or in the direction of convergence of the taper *a²*.

40 The nut *t* may be shifted into or out of engagement with the screw by a handle *t'*. *w* is a stop or gage which determines the starting point of the carriage and against which it is shifted after each traverse to the right.

45 Assuming the mandrel carrying the body *A* is held clamped between the two face plates, the operator passes the device *o* one or more times around the body *A* and then forms a bight in its free end around the 50 hook *s*. In doing this he preferably draws the device *o* sufficiently taut so that its wrappings, which lie side by side, will contract the body *A* to the tapered form of the mandrel, creasing or wrinkling the material 55 thereof, the creases or wrinkles thus produced usually being formed in a way to project or reach all in the direction in which the winding or wrapping takes place. Then, while holding the free end of the device *o* 60 so as to maintain the latter taut, the mandrel with the body *A* is rotated relatively to the device by setting the pulley in rotation, while meanwhile the device is traversed longitudinally of the axis of the mandrel because of the engagement of the screw *u* with

70 the nut *t* which at the outset has been established. The wrinkles or creases, generated as the result of wrapping the cord *o* around the body *A* in the tapered region of the mandrel, will thus be developed or continued and starting as more or less minute ones they will usually reach, and also increase in width to the transverse place where the constricting pressure is made to stop progressing toward the apex of the taper. 75 The folds or creases are not necessarily all generated in the same transverse plane. Some, as those marked 1 in Fig. 4, will start about where the taper *a²* begins and others, as 2, will start further on, in alternation with the folds or creases 1. In any event, as the result of the constricting pressure, the sheet material of the body *A* is, as it were, progressively molded to the form of the conical portion *a²* of the mandrel, the folds or creases being so sharp and well defined that, especially with the wax present on the paper, the tapered form given the article *A* is of a lasting and substantial character. Instead of wrapping the cord *o* 80 around the body *A* in the region of the tapered portion of the mandrel it might be wrapped around the cylindrical portion of the mandrel so that upon being drawn taut and the rotation and traverse being established the forming of the creases or wrinkles will be the result from the outset of slippage of the wrappings or convolutions of the cord.

85 In forming a milk bottle with a tapered portion provision should be made for a head or enlargement thereon and also for a seat within the head or enlargement for a bottle cap, such as the usual past-board cap. Therefore the constricting pressure may be 90 maintained so that it first encounters the angle at 3 in Figs. 2 and 3 and then passes off to the end of the tube *A*, so as to form the enlargement or head 4 and the interior 95 seat 5 for the bottle cap, the creased or folded formation of course in such case continuing to the end of the tube, since it is still contracted in diameter. When the head 100 4 and shoulder 5 have thus been formed, the edge portion of the tube may if desired be 105 inturned, as at 6 in Fig. 5 to reinforce the head and give a finish thereto.

110 On the shaping of each article as described the device *o* is released and removed, the wheel *n* turned so that mandrel carrying the 115 article may be removed, and the nut *t* disconnected and the carriage slid back, whereupon the apparatus is ready for another forming operation.

120 Having thus fully described my invention, what I claim as new and desire to secure by Letters Patent is:—

125 1. The herein-described method of forming a substantially tubular body of yielding material with a tapered portion which consists 130

in placing said body on a tapered mandrel and then applying constricting pressure to the body in a zone cutting the tapered portion of the mandrel and simultaneously causing relative rotation around the axis of the body as between said body and the pressure-applying medium and also effecting movement of one of the latter relatively to the other lengthwise of said axis and so that said pressure will progress in the direction of convergence of the taper.

10 2. The herein-described method of forming a substantially tubular body of yielding material with a tapered portion which consists in placing said body on a tapered mandrel and then applying continuous constricting pressure to the body in a zone cutting the tapered portion of the mandrel and simultaneously causing relative rotation 15 around the axis of the body as between said body and the pressure-applying medium and also effecting movement of one of the latter relatively to the other lengthwise of said axis and so that said pressure will progress in the direction of convergence of the taper.

20 3. The herein-described method of forming a substantially tubular body of yielding material with a tapered portion which consists in placing said body on a tapered mandrel having a shoulder at the smaller end of and facing reversely to the taper and then applying constricting pressure to the body in a zone cutting the tapered portion of the 25 mandrel and simultaneously causing relative

rotation around the axis of the body as between said body and the pressure-applying medium and also effecting movement of one of the latter relatively to the other lengthwise of said axis and so that said pressure 40 will progress in the direction of convergence of the taper and past the shoulder.

4. The herein-described method of forming a substantially tubular body of yielding material with a tapered portion which consists in placing said body on a tapered mandrel whose greatest diameter said body interiorly approximates and then wrapping an attenuated flexible device around the body in the region of the tapered portion of the 45 mandrel with sufficient constricting pressure to contract said body to the tapered portion of the mandrel, starting the wrapping in a zone approximating the greatest diameter of the mandrel.

5. The herein-described method of forming a substantially tubular body of yielding material with a tapered portion which consists in placing said body on a tapered mandrel and then applying continuous constricting pressure to the body in a zone cutting the tapered portion of the mandrel and also effecting movement as between said body and the pressure-applying medium lengthwise of the axis of said body and so that said pressure 50 will progress in the direction of convergence of the taper.

In testimony whereof I affix my signature.

MACK M. SCHWER.
